Des. 181,948
Patented Jan. 21, 1958

181,948

LIQUID FUEL CAN

Joseph E. Scanland, Des Moines, Iowa, assignor to New Monarch Machine & Stamping Company, Des Moines, Iowa, a corporation of Iowa

Application October 21, 1957, Serial No. 48,178

Term of patent 14 years

(Cl. D58—17)

Fig. 1 is a perspective view of a liquid fuel can embodying my new design.

Fig. 2 is a top plan view thereof.

Fig. 3 is an elevational view thereof.

Fig. 4 is an elevational view from one end thereof.

Fig. 5 is an elevational view from the opposite end thereof.

I claim:

The ornamental design for a liquid fuel can, substantially as shown.
